SHRINK FIXTURE

Oliver O. Rieser, Oak Park, Ill., assignor to The Richardson Company, Lockland, Ohio, a corporation of Ohio

Application September 16, 1935, Serial No. 40,680

15 Claims.

(Cl. 18—2)

My invention relates to shrink fixtures for use with rubber battery boxes after they have been removed from the vulcanizing mold; however, I do not intend to limit myself to this specific use, 5 since other uses of my invention will be apparent to those skilled in the art, and I merely describe my preferred form as exemplary of a use of my invention.

Rubber battery boxes are molded from a suitable rubber composition in a hot mold, in which they are also preferably vulcanized. When the formed and vulcanized box is taken from the mold, it is quite hot and somewhat soft; and while it is cooling it is very apt to shrink and warp out 10 of shape. It has been one practice in the art to plunge the hot box in cool water and thus to cool it quickly. This procedure has the decided disadvantage of providing no control of warping and shrinking. It has also been the practice in some 15 instances to place the box over a mandrel or core conformed to the inside of the box and to permit it to cool while on this mandrel. This procedure, while better than the former, has the disadvantage of permitting the edges of the box to 20 warp away from the mandrel and out of shape. The cooling of a formed rubber battery box while maintaining its shape is a difficult thing, and is 25 the primary problem to which my invention is addressed.

30 It is an object of my invention to provide a shrinking fixture which, while permitting and assisting the box to cool, will insure that the box, and especially the edges, will not warp and shrink out of shape.

35 It is a further object of my invention to provide a shrinking fixture which accomplishes the above, and which may be readily and quickly applied to the box.

40 A further object of my invention is to provide a shrinking fixture which permits the rapid cooling of the box by the use of rapid cooling media without the usual disadvantages of warping and shrinking inherent in rapid cooling.

45 These and other objects of my invention which will be set forth hereinafter, or will be apparent to one skilled in the art upon reading these specifications, I accomplish by that certain construction and arrangement of parts of which I shall now describe a preferred embodiment. Reference 50 is now made to the drawings which form a part thereof, and in which—

Figure 1 is a plan view of my novel shrinking fixture.

55 Figure 2 is a section thereof taken on the section line 2—2 of Figure 1.

Figure 3 is a perspective view of the latching pin.

Figure 4 is an elevational view of my novel shrinking fixture.

Briefly in the practice of my invention I provide 5 a core or mandrel so configured as to conform to the inside of the finished and cool battery box, through which I run cool water. The hot box is placed over this core, and a spring frame is resiliently clamped around the edge of the box pressing 10 it against the core. A stripper is provided for stripping the cooled box from the core, all of these parts being mounted in a convenient installation.

Referring to the drawings, I provide a core or mandrel 2 divided into three parts to conform to 15 the inside of the cells of a battery box 1. This core 2 is elongated so that its top will seat against the inside of the bottom of the box 1, while the other end of the core will project substantially therebeyond. Water to cool the core 2 is run 20 through it by means of the passageways 10.

The encircling frame 3 comprises four sides of strap metal and hinged to each other by the hinges and pintles 12. There is an inner frame 4 composed of four strips which are independent of 25 each other. These strips 4 contain a plurality of studs projecting therefrom with their shanks slidably riding or journaled in holes 13 in the outer frame 3. There are heads 5a on the ends of these studs 5 to limit the distance the inner strips 4 may 30 come away from the frame 3. Compression springs 6 are placed around the shanks of the studs 5 between the inner strips 4 and the outer frame 3.

The two free ends 3a and 3b of the frame 3 carry arms 11 and 11' pivoted or hinged to them. These arms 11 and 11' hold the frame 3 in a rectangular shape, when engaged. To accomplish 35 this, the two ends 3a and 3b are brought together to form a right angle by abutment, the arms 11 and 11' have cut-out notches 11a in the form of a 40 right angle, and are hinged at one leg of this angle so that when the arms 11 and 11' are brought together and lapped these cut-out notches will lie over the corner of the two ends 3a and 3b and hold 45 them in position. There is a hole 12 in each of the arms 11 and 11' which register when they are overlapped, and a pin 14 is provided which is slipped into these two holes and hold the two arms 11 and 11' in position. This pin 14 may have a 50 bent over portion or arm 14a to prevent it from falling completely through the holes.

The frame 3 is positioned around the core 2 so that when it is in the closed position it will be concentric therewith and is so positioned in a vertical position with respect to the core 2, that 55

it will encompass and cover the upper or edge portion of a battery box 1 placed in position on the core 2. The frame 3 is held in position by means of a bracket 15 which is bolted at one end 5 by means of bolts 16 to an intermediate portion of the frame 3, and at the other end to the core 2 itself. The bracket 15 is so conformed and bent as to maintain the position of the frame 3 concentric to the core 2, when the frame is closed.

10 In the preferred form shown in the drawings, the three segments of the core 2 and a base 17 are all cast in one piece. This greatly facilitates construction and makes the cooling of the core 2 much more uniform. The core 2 carrying the frame 3 may conveniently be mounted upside down on a table 18 as illustrated in Figure 4.

From the above it is apparent that the frame 3 may be opened away from the core 2 by releasing the arms 11 and 11' after removing the pin 20 14 and opening the sections of the frame 3 on its hinges 12. The bracket 15 holds the frame 3 in open position and in readiness for placing it around a battery case 1 placed over the core. In operation the hot battery box is placed on the core 2 when the frame 3 is in the opened position, and then the frame 3 is closed around the battery 1. The strips 4 press the edge of the box 1 against the core 2 and prevent it from warping while it is cooling.

30 To remove the box 1 from the core 2 after it has cooled, I provide a stripper comprising two rods 20 journaled in the base 17 and terminating in a common yoke or arbor 21. Pins 9 are placed through the rods 20 in such a position that the ends of the rods will be below the line of the edge of the box 1 when it is in place on the core 2. The ends of the rods 20 may terminate in abutments 20a so as to give a broad bearing surface and not to mar the edge of the box 1 in stripping. There is an operating lever 21 pivoted at a point along its length to the table 18. One end of this lever 21 is pivoted to the arbor 21a. By rocking the lever 21 it is apparent that the ends of the rods 20 will move upwardly and contact the edge of the box 1 lifting it from the core 2 on further movement.

In my preferred embodiment I provide a control valve 22 for controlling the inflow of the cooling water.

50 In operation, the hot battery box 1 is taken out of the mold and placed over the core 2 after the frame 3 has been opened to permit the placing of the box 1 between it and the core 2. The box 1 is pushed down over the core 2 until the core 2 completely fills it. The frame 3 is then closed and locked so that the sections 4 will press the sides of the box 1 against the core 2. This will insure the even cooling of the box without any undesirable warping or shrinking. When the 60 box has been cooled by the water running through the core, the frame 3 is opened and the stripper actuated. The cooling of a rubber box in this manner insures that the box when finished and cooled will conform to exact predetermined dimensional specifications, and will have true and parallel sides and dividing walls.

It is to be understood that modifications of my preferred embodiment may be made without departing from the spirit of my invention.

70 Having thus described my invention, what I claim as new and desire to secure by Letters Patent, is:—

1. In a shrink fixture, the combination of a cooling mandrel and a resilient jacket encircling 75 the same.

2. The process of cooling a rubber box which consists in placing the box on a cooling mandrel and resiliently externally pressing the same, at least at its upper edges, against the mandrel.

3. In a shrink fixture, the combination of a 5 cooling mandrel and a resilient jacket encircling the same, said jacket comprising an outer hinged frame concentric with said mandrel when closed, and an inner frame resiliently urged from said outer frame and toward the mandrel.

10 4. In a shrink fixture, the combination of a cooling mandrel, means for flowing water therethrough, means for stripping said mandrel, and a jacket removably encircling the same.

15 5. In a shrink fixture, the combination of a cooling mandrel, means for flowing water therethrough, means for stripping said mandrel, and a jacket removably encircling the same, said jacket comprising hinged sections and means for holding said sections in a continuous encircling 20 strip, inner pads urged from said sections toward said mandrel by means of springs, and a bracket for holding said jacket in concentric position around said mandrel when said jacket is in a continuous encircling strip.

25 6. In a shrink fixture, the combination of a cooling mandrel, means for flowing water therethrough, means for stripping said mandrel, and a jacket removably encircling the same, said jacket comprising hinged sections and means for 30 holding said sections in a continuous encircling strip, inner pads urged from said sections toward said mandrel by means of springs, and a bracket for holding said jacket in concentric position around said mandrel when said jacket is in a 35 continuous encircling strip, said bracket holding said jacket to said mandrel.

7. A shrink frame comprising four strip sections hinged to each other and formable into a rectangle, means for holding said frame in rectangular form, said means comprising an arm pivoted to each end of the strip sections, right angular notches in said arms and so positioned that when said arms are lapped they will form a corner, and means for holding said arms in lapped relation, four pressure pads attached parallel to said four sections, and means for urging said pressure pads away from said sections so as to form a resiliently expandable rectangle when said sections are in the form of a frame, a water cooled core of generally rectangular cross section, and means for holding said frame concentric therewith, said means comprising a bracket attached to one of said sections and the side of said core.

55 8. A shrink frame comprising four strip sections hinged to each other and formable into a rectangle, means for holding said frame in rectangular form, said means comprising an arm pivoted to each end of the strip sections, right 60 angular notches in said arms and so positioned that when said arms are lapped they will form a corner, and means for holding said arms in lapped relation, four pressure pads attached parallel to said four sections, and means for urging 65 said pressure pads away from said sections so as to form a resiliently expandable rectangle when said sections are in the form of a frame, a water cooled core of generally rectangular cross section, and means for holding said frame concentric therewith, said means comprising a bracket attached to one of said sections and the side of said core, and stripping means associated with said core comprising slidably abutments adjacent the sides of said core.

9. In a shrink fixture, the combination of a water cooled core, resilient holding means forming a band around said core, and stripping means for said core, said resilient band being concentric with said core, and means for opening said band to permit insertion of a hollow article over said core and between said resilient band and said core.

10. In a shrink fixture for cooling a rubber box, the combination of a water cooled core configured to fit into said box, a resilient band surrounding a portion of said box and said core, said band being splittable in order to permit inserting said box over said core, and stripping means for said core.

11. A shrink fixture for cooling a box, comprising a water cooled mandrel configured so as to fill said box, and means encircling the sides of said box and said core and pressing said sides against said core.

12. A shrink fixture for cooling a box, comprising a water cooled mandrel configured so as to fill said box, and means encircling the sides of said box and said core and pressing said sides against said core, said encircling means being splittable.

13. In combination a table, an inverted core on said table adapted to have a hollow vulcanized article placed thereover, a pivoted, separable, articulated, resilient frame for pressing said article against said core, and supporting means for said frame, said means permitting separation thereof.

14. In combination a table, an inverted core on said table adapted to have a hollow vulcanized article placed thereover, a pivoted, separable, articulated, resilient frame for pressing said article against said core, and supporting means for said frame, said means permitting separation thereof, and stripping means for pressing said article upwardly from said core.

15. In combination a table, an inverted core on said table adapted to have a hollow vulcanized article placed thereover, a pivoted, separable, articulated, resilient frame for pressing said article against said core, and supporting means for said frame, said means permitting separation thereof, stripping means for pressing said article upwardly from said core, and operating means for said stripping means located beneath said table.

OLIVER O. RIESER.
